(57) **CLAIM**

The ornamental design for a slidable dish rack as shown and described.

DESCRIPTION

FIG. 1 is a front perspective view of a slidable dish rack showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is another front perspective view showing a center rack being removed;

FIG. 10 is the other front perspective view showing two side racks being removed;

FIG. 11 is the other front perspective view showing a shelf being pulled out; and,

FIG. 12 is an enlarged additional view of FIG. 1 showing a portion of the base rack with all of the center and side racks being removed.

The broken line portions of the slidable dish rack in FIGS. 1-12 represent unclaimed portions of the slidable dish rack and form no part of the claimed design.
